Dec. 2016

Edward Burke of Philadelphia, Penna.

Letters Patent No. 2016-Dated December 20-1864.

Design for a Match Box.

The schedule referred to in these letters Patent and making part of the same.

To all whom it may concern:

Be it known that Edward Burke, of Philadelphia, County of Philadelphia State of Pennsylvania, have invented and produced a new and original design for a Match Box; and I do hereby declare the accompanying drawing with the following explanation of the same to form a full, clear and exact description of the said design.

Reference to the accompanying drawing which forms a part of this specification.

Fig. 1 is a perspective view of my improved match box, and

Fig. 2 a transverse vertical section.

A wooden case which consists of the base and sides & back and curved top & the outside of the latter being roughened or serrated. To the top of the case near its points of junction with the back are secured two plates ^{of} iron each of which is an opening, &c. Within the case A wooden cylinder B, which has an opening at the top, and which is closed at the ends, thus constituting a receptacle for the matches, the said cylinder turning on two pins C, which project from the sides through the sides & back of the case.

At the outer edge of the opening in the cylinder is an ornamental piton as shown in the drawing.

I claim as my invention and desire to secure by Letters Patent

The shape and configuration of the within described match box.

In testimony whereof I have signed my name to this specification in the presence of two subscribing witnesses.
